UNITED STATES PATENT OFFICE.

ALBANUS PHILLIPS, OF CAMBRIDGE, MARYLAND.

CONSTRUCTION OF OYSTER-SHUCKING ESTABLISHMENTS.

1,217,821.

Specification of Letters Patent. Patented Feb. 27, 1917.

Application filed September 29, 1916. Serial No. 122,951.

To all whom it may concern:

Be it known that I, ALBANUS PHILLIPS, a citizen of the United States, residing at Cambridge, in the county of Dorchester and State of Maryland, have invented certain new and useful Improvements in the Construction of Oyster-Shucking Establishments, of which the following is a specification, reference being had therein to the accompanying drawing.

10 This invention relates to improvements in the construction of oyster shucking establishments, having in view a number of important objects.

15 One of which is to provide a construction which does away with the dirt, sand, mud, damp and cold and uncomfortable surroundings and conditions usually found in oyster shucking establishments, thereby providing

20 a construction and arrangement which is clean and, therefore, sanitary; which is dry and warm; well ventilated and well lighted thereby making it comfortable for the workers, thus materially increasing their efficiency.

25 Another object of my present invention is to decrease the cost of shucking oysters by providing means whereby the oysters are supplied by gravity (and, therefore, automatically)

30 to the shuckers on the front edge of the shucking tables as rapidly as they are used, which materially increases the efficiency of the shuckers, and, consequently, correspondingly decreases the cost of shucking the oysters.

35 Another object of my invention is to provide a construction whereby all the water and liquor from the oysters are automatically conveyed from the shuckers' tables by gravity to a suitable trough or passage through which the water and liquor are carried off and prevented from accumulating on the floor of the building, therefore making it dry, clean, sanitary and comfortable.

40 Another object of my invention is to provide a construction whereby the shuckers' benches and all parts connected therewith, including the trough or passageway for the disposal of the water and liquor, can be readily and individually removed for cleaning purposes.

45 Another object of my invention is to eliminate the usual discord among the shuckers due to an alleged discrimination claimed by 50 one getting better oysters than another, and

thereby eliminating all argument in that respect which is found also to materially increase the efficiency of the workers.

Another object of my invention is to so construct and arrange the structure that the women can be separated from the men and the white workers from the colored, all of which serve materially for harmony among the workers and adds much to their efficiency and correspondingly decreases the cost. 60

Another object of my invention is to so construct and arrange the structure that the clothing of the shuckers is kept free from mud, dirt and sand, free from shells and water and always clean, together with clean 70 and dry floors which is usually not true in oyster shucking establishments.

Another object of my invention is to effect a material saving by providing an individual inspection of the shells of the shucked oysters. In this way carelessness of the shuckers in throwing out unshucked oysters and waste in not cleanly cutting the oysters from the shells are readily observable upon the individual inspection and affords a means for 80 stopping such carelessness. In the practical operation of this improvement, this individual inspection is found to effect a very material saving. 75

There are further objects and advantages 85 accruing from the use of my improvement which will be referred to hereinafter.

In the accompanying drawings—

Figure 1 is a sectional view of an oyster shucking establishment which embodies my 90 invention.

Fig. 2 is a perspective view of a part of the structure embodying my invention.

Fig. 3 is an enlarged vertical sectional view taken transversely through one of the 95 oyster chutes and shucking benches.

Fig. 4 is a partial plan view showing the conveying runways to the chutes and the conveying platform communicating with the said runways. 100

Those who are familiar with the oyster packing industry will know how uninviting and uncomfortable, gloomy and unsanitary these establishments usually are, because of the usual poor lighting and heating, and because of the wet and dirty floors found in such establishments due to the accumulation of oyster shells with their accompanying dampness, mud, sand, and other uninviting conditions. These conditions exist to such 110

- an extent in the ordinary oyster shucking establishments, that persons visiting them are apt to lose much of their appetite for these otherwise very palatable bivalves. All of 5 these unattractive, unsanitary, and uncomfortable conditions heretofore existing in establishments of this character are overcome by my improved arrangement and structure, to such an extent that the impression given 10 to those visiting the establishment is cleanliness, sanitary and comfortable conditions, and quite the opposite impression is obtained from that common to such establishments heretofore.
- 15 In carrying out my present improvement, I provide a structure made up of a ground or inspection room 1, and a working or shucking room 2. This structure preferably, though not necessarily, will have its beams 3 20 set in concrete foundation 4. The top 5 of the structure is provided with a plurality of skylights 6, for the purpose of providing light from above and is provided with a suitable number of wall windows 7 for providing 25 side lighting. A suitable number of passageways or doors 8 are provided for the working or shucking floor and similar doors or passages 9 for the inspection floor 1.
- 30 My improved shucking benches and oyster supply therefor is shown clearly in Fig. 3. It comprises an oyster chute 10 having at its upper end a laterally extending supply runway 11. The upper end is open as shown at 10 to receive the oysters either from a wheelbarrow or from a suitable conveyer, neither of which is here shown. The chute 10 will be filled with oysters and they flow out the lower end on to a separating bar 14, which has inclined sides 15 and a central projection 35 40 45 50 55 60 65 70 75 80 85 90 95 100 105 110 115 120 125 130
- 16, which serve to cause the oysters to fall to each side of the separating or division bar 15 and be deposited at the inner edge of the shucker's bench 17. These shucker benches or stations may or may not be provided with a supplemental board 18, for the purpose of taking the wear of the shucking operations. Preferably, such a board is used, but it is not essential to the carrying out of my present invention. These shucker benches 17 are located, as shown, at each side of the division or separating bar 15, so that there is a shucker's bench at each side of the separating bar 15, and at each side of the lower end of the oyster chute 10.
- 55 Each of these shucker benches 17 is provided with a shell opening 19, and when a supplemental shucker board 18 is used, it is provided with a registering shell opening 20. These shell openings communicate with 60 a separate shell receiving chute 21, which, preferably, converge under the shucker benches 17 and extend through the floor 22 of the working or shucking room 1. The lower ends of these shell chutes 21, are provided with hinged doors 23, adapted to be

held closed or permitted to open by suitable spring latches 24. The shuckers push or drop the shells through the openings 19 as the oysters are shucked and they accumulate in the chutes 21, so that the shells of the 70 shucked oysters and any unshucked oysters of each shucker is retained within these chutes until they can be inspected, when the door of the chute is opened and the contents thereof are deposited on a wheelbarrow or 75 suitable conveyer, not shown, which provides an individual inspection station.

In this way a constant watch can be kept 80 on each individual shucker at the inspection station to see that there is no waste in the way of unshucked oysters and any waste in the failing to cleanly cut the oyster from the shell. In large establishments where a large 85 number of shuckers are working, it is found that there is a large waste in unshucked 90 oysters and in failing to cleanly cut the oysters from the shells. As the shucked oysters are sold by measure, it has been found in practice that there is a large waste where there is no check on the carelessness in 95 this respect of the shuckers. It is also found in practice that with an inspection and check on the shuckers a large saving is accomplished and to an extent that is unbelievable to those who have not actually tested it out. 100

The shucked oysters, of course, are deposited by the shucker in a suitable receptacle (not shown) and the waste liquor and water from the oysters run down the incline shucker benches 17 and into a trough or passage 25 located directly under the inner edges of the adjacent shucking benches 17. The shucking benches and the division or separating bar 15 are made of rough unplaned lumber, so that they do not tightly 105 fit and the liquor and water find their way under the division bar 15 between its under projection 26 and the adjacent rough edges of the shucking tables 17 to the trough 25 below. This waste liquor and water are 110 then conveyed away to any desired point or points through the trough or passage 25. In this way the floor 22 of the shucking room is kept dry and comfortable to the shuckers, for the waste water and liquor are 115 not permitted to accumulate on the floor as it does under the old shucking system.

The division bar 15 and the shucker's table 17 are removable so access is readily had to the trough 25, for the purpose of 120 cleaning it out when necessary.

These shucking benches can be made of any desired length and are preferably placed in rows in the building, as shown in Figs. 1 and 2, and the oyster chutes are 125 located above the benches, as shown, and in this way the oyster chutes and the benches sufficiently divide up the shucking room to avoid the disagreeable drafts that are occasioned in the usual oyster shucking room. 130

Furthermore, it enables the conveying runway 11 to be provided which extends along the oyster chutes 10 and longitudinal the benches, so that the oysters can be conveyed 5 from a storage or supply point and dumped into the separate oyster chutes 10. To avoid the falling of the oysters, water or dampness or drippings from the runway on to the shuckers below, the runway is at a slight 10 angle toward the oyster chutes so that any water or drippings will be conveyed into the chute and the falling of the oysters on the edge off the runway 11 is prevented by a suitable board or flange 27, and to prevent 15 the oysters from being thrown over the opposite edge of the upper end of the chute 10 and thereby fall on the workers below, the wall of the chute is extended upward above its upper end, as shown at 28. In this way 20 the falling of the water and oysters from the conveying runway above is prevented.

The division bar 15 serves to cause a supply of oysters to always be provided to the shuckers at opposite sides thereof. This arrangement eliminates discussion and discord 25 between the shuckers about the character of the oysters they are getting and it provides an uninterrupted and constant supply of oysters to the shuckers. Owing to the 30 straight sides of the chutes 10, the oysters readily fall therethrough to the division bars and fall to the opposite sides thereof in convenient locations for the shuckers.

A further advantage of this construction 35 is that the oysters are shucked in the order in which they are supplied to the shuckers. That is to say, the oysters first supplied must be shucked and there cannot be any accumulation of stale oysters as does occur 40 where there is no way to insure the oysters being shucked in the order in which they are delivered to the shuckers. Any oysters left in the chute 10 at any time, must be first shucked before any other oysters are delivered 45 to the shuckers, so that any accumulation of stale oysters is absolutely avoided.

A supply platform or runway 29 is provided at one side of the building in the same plane as the conveying runways 11, and 50 communicating passages 30 are provided. The oysters may be taken from the boat (not shown) and deposited on the shelf or supply runway 29, or they may be taken thereto from a storage room in any convenient manner. They are then conveyed in a suitable 55 way from the supply runway 29 to the chutes 10 of those oyster benches that are being used.

It will be understood that the rows of 60 shucking benches may be of any desired length for the purpose of accommodating any desired number of shuckers without affecting in any manner the spirit and scope of my invention.

65 I have found in actual practice of this im-

proved shucking establishment, an increase in efficiency, easily equal to fifty per cent. over the old methods in addition to affording sanitary, comfortable and attractive surroundings, such as not heretofore known in 70 establishments of this character.

I desire it to be understood that certain modifications can be made in the specific construction and arrangement of parts in my improved establishment and still retain 75 many of the advantages thereof without departing from the scope of the broad invention here disclosed. For instance, instead of having the individual oyster chutes 10 for the individual shucking tables, these could be made one long chute, but it would lose 80 some of the advantages which have been pointed out, yet it would be a means for feeding the oysters by gravity to the shucking tables and therefore be an advantage. 85

Also a single continuous shell chute for all of the various tables could be provided instead of individual chutes. This would lose 90 very largely the advantage of individual inspection, but it would at the same time provide a means for instantly getting the shells and other dirty substances away from the shucking room.

It will be obvious to a skilled mechanic that some of the details could be changed 95 without deviating from the idea of the invention, and, therefore, without departing from the intended scope of the claims hereto attached.

Having thus described my invention, what 100 I claim and desire to secure by Letters Patent is:

1. An improved oyster shucking establishment comprising a shucking room provided with a shucking bench, a shell chute for each bench extending downwardly therefrom and having a closure at its lower portion, an oyster supply chute above the shucking table whereby oysters are supplied to the shucking table by gravity and the shucked oyster shells conveyed to a point 105 below where they can be individually inspected.

2. An improved shucking establishment comprising a shucking room, having a shucking bench, an oyster shell chute extending from the bench through the floor, and an oyster chute above the shucking bench having a lower open end located directly above one edge of the shucking bench to deliver 115 oysters thereto by gravity whereby the oysters are supplied to the shucker and the shells with their accompanying dirt instantly conveyed from the shucking room. 120

3. An improved shucking establishment 125 comprising a shucking room having a shucking bench, an oyster shell chute extending from the bench through the floor whereby the oyster shells may be instantly conveyed from the shucking room, an oyster chute 130

above the shucking bench and conveying oysters by gravity thereto, and a liquor and water conveyer communicating with the shucking bench whereby the water and 5 oyster shells are instantly conveyed away from the shucking bench.

4. An oyster shucking establishment comprising a shucking room, a shucking bench therein declining away from the position of 10 the shucker, and a trough or passageway at the lower end of the shucking bench for conveying away the water and liquor from the oysters.

5. An improved shucking establishment 15 comprising a shucking room, a plurality of shucking tables therein declining away from the shuckers, and a liquid conveying trough extending along and common to the shucking benches and receiving the liquid there- 20 from and conveying it away.

6. An improved shucking establishment comprising a shucking room, a plurality of shucking tables therein, each shucking table having a separate shell chute extending 25 therefrom and through the floor, and an oyster chute above each shucking table for conveying the oysters by gravity thereto, and a liquid conveyer in communication with the several shucking tables for conveying 30 away the liquid and water from the oysters.

7. An improved shucking establishment, comprising a shucking room, an oyster chute therein having an open lower end, a 35 shucking station within the shucking room, a shell inspection station, and means for conveying the shells from the shucking station to the inspection station.

8. An improved shucking establishment, 40 comprising a shucking room, an oyster chute therein having an open lower end, shucking stations below the lower end of the chute and at opposite sides thereof, and an inspection station for each shucking station, 45 and shell chutes extending from the shucking stations to the inspection stations.

9. An improved shucking establishment comprising a shucking floor, an oyster chute therein having open upper and lower ends, 50 shucking tables located under the open lower end of the chute and extending in opposite directions therefrom, oyster shell chutes extending from the shucking tables through the floor of the shucking room, and 55 a liquid conveyer in communication with the shucking tables whereby the oyster shells and the liquid are instantly conveyed from the shucking tables, for the purpose described.

60 10. An improved shucking establishment comprising a shucking floor, an inspection floor therebelow, a plurality of shucking tables in the shucking room, a plurality of oyster chutes above the tables for conveying 65 oysters by gravity thereto, and an oyster

shell chute for each table and extending through the shucking room floor, the lower portion of the chute provided with a door, whereby the shucked oyster shells and other objects in each shell chute can be individually 70 inspected for the purpose described.

11. An improved shucking establishment comprising a shucking room, an inspection room therebelow, of a plurality of individual shucking tables in the shucking room, 75 a plurality of oyster supply chutes thereabove with their lower ends delivering the oysters by gravity to the individual shucking tables, a shell chute for each table and extending through the floor of the shucking 80 room and provided with a door at its lower end, and a liquid conveyer common to and in communication with each of the shucking tables, whereby the liquid and the shells from the shucking tables are instantly conveyed 85 away and whereby the contents of each shell chute can be individually inspected, for the purpose described.

12. An improved shucking establishment comprising a shucking room, a plurality of 90 shucking tables therein, an oyster chute above the tables for supplying oysters thereto, each table having a shell opening, a shell chute in communication with said opening and extending through the shucking floor, 95 the shucking tables arranged in opposite directions and facing each other with their inner edges under the lower ends of the oyster chute, and a liquid conveyer with an open top under the inner edges of the shucking 100 tables, all combined for the purpose described.

13. An improved shucking establishment comprising a shucking room, an oyster chute 105 therein, shucking tables below the lower end of the chute and extending in opposite directions, the shucking chute having an open lower end, and a division bar with inclined sides located between the inner edges of the shucking tables and below the open end of 110 the chute for directing the oysters to both tables.

14. An improved shucking establishment comprising a shucking room, an oyster chute 115 therein, a plurality of shucking tables arranged below the open end of the chute and extending in opposite directions, an open top liquid receiving and conveying trough below the inner edges of the shucking tables, and a removable separating bar between the 120 inner edges of the shucking tables and below the lower end of the oyster chute, all combined for the purpose described.

15. An improved shucking establishment comprising a shucking room, a plurality of 125 shucking tables arranged therein, an oyster chute above the shucking tables with open upper and lower ends, and an oyster conveying runway at one side of the upper end of the oyster chute whereby oysters may be 130

conveyed and supplied at various points of the chute for the various shucking tables.

16. An improved shucking establishment comprising a shucking room, a plurality of shucking tables therein, an oyster chute above the shucking tables and having open upper and lower ends, a conveying runway at one side of the upper end of the oyster chute, the outer edge of the runway having a vertical wall and the side of the chute opposite the runway extending above the chute, all for the purpose described.

17. An improved oyster shucking establishment comprising a shucking room, a plurality of shucking tables therein arranged in a row, a plurality of oyster chutes above the tables and also arranged in a corresponding row, the said chutes having open upper and lower ends, a runway at one side of the upper ends of the said chutes whereby oysters can be delivered to the respective chutes and thereby to the respective tables.

18. An improved shucking establishment comprising a shucking room, a plurality of shucking tables therein arranged in parallel rows, oyster chutes arranged in parallel rows over the tables and having open upper and lower ends, a runway at one side of the upper ends of the parallel rows of the chutes, and a supply runway extending transverse and connecting the ends of the said runways, whereby oysters can be carried from the said supply runway and delivered to the

said oyster chutes at various points to supply the various tables.

19. An improved oyster shucking establishment, comprising a shucking room, a shucking bench or station, means for supplying the shucking station with oysters, an inspection station removed from the shucking station, and means for conveying the shells from the shucking station to the inspection station.

20. An improved oyster shucking establishment, comprising a shucking room provided with a shucking station, an inspection room apart from the shucking room provided with a shell inspection station, and means for conveying the shells from the shucking station to the inspection station.

21. An improved oyster shucking establishment, comprising a shucking room provided with a plurality of shucking stations, an inspection room apart from the shucking room provided with a plurality of inspection stations, one for each shucking station, and means for separately conveying the shells from each shucking station to its separate inspection station, for the purpose described.

In testimony whereof I hereunto affix my signature in the presence of two witnesses.

ALBANUS PHILLIPS.
